POLE CLIMBER

Walter D. McCammond, Flushing, N. Y., assignor, by mesne assignments, to Mine Safety Appliances Company, Pittsburgh, Pa., a corporation of Pennsylvania

Application December 13, 1947, Serial No. 791,525

5 Claims. (Cl. 227—27)

1

This invention relates to pole climbers such as those used by telephone linemen, and more particularly to climbers having removable spurs.

It is among the objects of this invention to provide a pole climber which has a spur that is readily removable from the leg iron, which is formed to safely hold the spur in position until it is desired to remove it, and which cannot release the spur as long as the wearer's weight is on the climber.

In accordance with this invention a leg iron of a pole climber has a shank and a foot-supporting portion. The lower end of the shank has a vertical slot in which is received a vertical rib projecting from the body of a removable spur that engages the outside of the shank around the slot. The upper end of the rib and the adjoining portion of the shank are provided with interengaging detents to hold the upper end of the spur in place. The lower end of the rib and the side walls of the slot are provided with aligned holes through which extends a removable pin. Preferably, the rib extends below the body of the spur, and a portion of the shank extends part way up the outer face of that extension. When the pin is removed, the rib can be lowered in the slot until the upper end of the spur is disengaged from the shank and swung outward, and then the spur can be lifted to pull the lower end of the rib out of the slot.

The preferred embodiment of the invention is illustrated in the accompanying drawings, in which Fig. 1 is a side view of my climber with the fastening straps broken away; Fig. 2 is a view of the spur side of the climber; Fig. 3 is an enlarged fragmentary view from the opposite side; Fig. 4 is a fragmentary vertical section through the lower portion of the climber, showing the spur in elevation; and Figs. 5 and 6 are inner and top views, respectively, of the spur alone.

Referring to the drawings, a leg iron has a shank 1 which has a flat upper portion adapted to extend up the inside of the leg of the wearer. This flat portion is reinforced by a central rib 2. Slidably mounted on the upper portion of the shank is a metal sleeve 3 that conforms to the shape of the shank. The sleeve and the rib are provided with a plurality of vertically spaced holes 4 through some of which cotter pins 5 extend for holding the sleeve in different vertically adjusted positions on the shank. The inner face of the sleeve carries a leather pad 7 for engaging the leg. Fastened to the outer face of the sleeve are wire loops 8 that support the usual strap 9 that can be buckled around the leg to hold the

2

upper end of the climber in place against the leg.

The lower end of the shank of the leg iron merges into a foot-supporting portion 11, or stirrup, adapted to extend beneath the shoe of the wearer directly in front of the heel. The outer end of this stirrup is curved upwardly and provided with a pair of upwardly converging slots 12 (Fig. 3). Straps 13 are fastened through these slots and are adapted to be buckled around the ankle in the usual manner to hold the foot in place in the stirrup.

The lower portion of the shank is provided with a spur 15 for digging into the pole up which the wearer wishes to climb. It is a feature of this invention that this spur is securely held in place, but yet it can be removed when it is desired to sharpen it or replace it. Accordingly, the lower portion of the shank is provided with a vertical slot 16 just wide enough to snugly receive a vertical rib 17 projecting inward from the body 18 of the spur. As shown in Figs. 5 and 6, the spur body is wider than the rib and projects beyond its top and opposite sides so that the body will overlap the sides of the slot and engage the outside of the shank, thereby positively limiting the distance that the spur can project into the shank. At the upper end of the slot the shank is provided with a recess 19 (Figs. 2 and 4) to permit the upper part of the spur body to fit into the shank so that it will not catch on anything.

In order to hold the upper end of the spur in slot 16, the upper end of rib 17 is provided with a downwardly extending notch 21 that receives a tongue 22 projecting down from the portion of the shank at the upper end of the slot. As shown in Fig. 4, the rib is held up high enough in the slot to keep the tongue in the notch by means of a removable pin 23 extending through aligned holes in the lower end of the rib and the side walls of the slot. This is the only purpose of the pin, which therefore need not be large, because the lower end of rib 17 is prevented from swinging out of the slot by a means of a portion or web 24 of the shank which extends part way up the outer side surface of the rib that extends below the spur body. As a safety measure, another pin 26 extends through the shank and across the slot directly below rib 17 so that if anything happens to the upper pin, the rib can not slide down in the slot and become released from tongue 22 at its upper end.

When it is desired to remove the spur from the shank, the two pins 23 and 26 are removed so that the rib can be lowered in the slot far enough to allow its upper end to be swung out

beneath the tongue. The spur then can be pulled upward to withdraw the lower end of its rib from the lower end of the slot behind web 24.

It will be noted that the spur is held safely in place in a simple manner, and that as long as the weight of the wearer is on the spur it cannot accidentally become disengaged from the leg iron because tongue 22 will be held down in notch 21. The width of the spur body prevents it from ever passing through the slot, while web 24 holds the lower end of rib 17 in the slot as long as the tongue is in the notch.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A pole climber comprising a leg iron having a shank and a foot-supporting portion, the lower end of the shank having a vertical slot therethrough, a removable spur having a body engaging the outside of the shank around the slot and having a vertical rib projecting into the slot, the upper end of the rib and the adjoining portion of the shank being provided with an interengaging vertical tongue and notch to hold the upper end of the spur in place, the lower end of said rib and the side walls of the slot being provided with aligned holes, and a removable pin extending through said holes.

2. A pole climber comprising a leg iron having a shank and a foot-supporting portion, the lower end of the shank having a vertical slot therethrough, a removable spur having a body engaging the outside of the shank around the slot and having a vertical rib projecting into the slot, the upper end of the rib being provided with a notch and the adjoining portion of the shank having a tongue projecting down into the notch to hold the upper end of the spur in place, the lower end of said rib and the side walls of the slot being provided with aligned holes, and a removable pin extending through said holes.

3. A pole climber comprising a leg iron having a shank and a foot-supporting portion, the lower end of the shank having a vertical slot therethrough, a removable spur having a body engaging the outside of the shank around the slot and having a vertical rib projecting into the slot and extending below said body, said shank having a portion extending part way up the outer face of said rib extension to hold the lower end of the rib in place, the upper end of the rib and the

adjoining portion of the shank being provided with interengaging detents to hold the upper end of the spur in place, the lower end of the rib and the side walls of the slot being provided with aligned holes, and a pin extending through said holes and removable therefrom to permit the rib to be lowered in said slot to disengage said detents, whereby the spur can be removed from the shank.

4. A pole climber comprising a leg iron having a shank and a foot-supporting portion, the lower end of the shank having a vertical slot therethrough, a removable spur having a body engaging the outside of the shank around the slot and having a vertical rib projecting into the slot and extending below said body, said shank having a portion extending part way up the outer face of said rib extension, the upper end of the rib being provided with a notch and the adjoining portion of the shank having a tongue projecting down into the notch to hold the upper end of the spur in place, the lower portion of said slot having two vertically spaced pairs of holes through its side walls, the lower end of the rib having a transverse hole through it aligned with the upper of said pair of holes and the other pair being below the rib, and pins extending through said holes and removable therefrom to permit the rib to be lowered in said slot to disengage said tongue and notch, whereby the spur can be removed from the shank.

5. A pole climber comprising a leg iron having a shank and a foot-supporting portion, the lower end of the shank having a vertical slot therethrough, a removable spur having a body engaging the outside of the shank around the slot and having a vertical rib projecting into the slot, the upper end of the rib being provided with a notch, the outside of the shank at the upper end of said slot being provided with a recess receiving the upper end of said spur body and forming a tongue projecting down into said notch to hold the upper end of the spur in place, the lower end of said rib and the side walls of the slot being provided with aligned holes, and a removable pin extending through said holes.
